UNITED STATES PATENT OFFICE.

WELFORD H. DIGGS, OF EMPORIA, KANSAS.

HITCHING DEVICE FOR TRACTORS.

1,232,245.

Specification of Letters Patent.

Patented July 3, 1917.

Application filed February 24, 1917. Serial No. 150,796.

To all whom it may concern:

Be it known that I, WELFORD H. DIGGS, a citizen of the United States, residing at Emporia, in the county of Lyon and State of Kansas, have invented new and useful Improvements in Hitching Devices for Tractors, of which the following is a specification.

This invention relates to hitching devices for tractors and it has for its object to provide a simple and improved hitching device which will be particularly adapted for hitching a plow or a gang plow to a tractor.

When a tractor is utilized for drawing a plow it is frequently found extremely difficult if not impossible to turn a square corner either to the right or to the left, this being due largely to the unvarying resistance exerted by the plow at the hitching point.

20 To overcome this objection is one of the objects of the invention.

A further object of the invention is to produce a hitching device of simple and improved construction whereby the motion 25 of the tractor in turning a corner will cause adjustment of the hitching point or point of draft to be effected in one direction or the other, thereby avoiding the objectionable side draft and facilitating the turning 30 of a sharp corner.

With these and other ends in view which will readily appear as the nature of the invention is better understood, the same consists in the improved construction and novel 35 arrangement and combination of parts which will be hereinafter fully described and particularly pointed out in the claims.

In the accompanying drawing has been 40 illustrated a simple and preferred form of the invention, it being, however, understood that no limitation is necessarily made to the precise structural details therein exhibited, but that changes, alterations and modifications within the scope of the claims may be 45 resorted to when desired.

In the drawing:

Figure 1 is a top plan view of a device constructed in accordance with the invention.

50 Fig. 2 is a side view of the same.

Fig. 3 is a sectional view taken on the line 3-3 in Fig. 1.

Fig. 4 is a horizontal sectional view taken on the line 4-4 in Fig. 3.

55 Corresponding parts in the several figures

of the drawing are denoted by like characters of reference.

A housing is provided, the same being constructed of top and bottom plates 15 and 16 of isosceles triangular form having a base of 60 relatively great length, said plates being spaced apart by spacing blocks 17 located in the angles adjacent to the base, and connected together by bolts or fastening members 18 extending through said blocks. The 65 inner side walls of the spacing blocks 17 are rounded to provide pockets 19. The top and bottom plates are provided with flanges 20 extending between the apex of the housing and the corners adjacent to the base thereof, 70 said flanges, which are suitably spaced apart, constituting track rails for a pair of rollers 21 carried by a hitching strap 22 one end of which extends within the housing. 23 is a hitching bar which is mounted adjacent to 75 the base of the housing, said bar being provided with lugs 24 entering recesses in the spacing blocks 17 where said lugs are engaged by the bolts or fastening members 18 whereby the hitching bar is securely connected with the housing. Said bar is provided with a plurality of apertures 25 for the passage of fastening members 26 whereby it is connected with the rearward ends of hitching straps 27 the forward ends of 85 which are adapted to be connected with a tractor with respect to which the hitching bar is thus capable of being transversely adjusted.

Secured within the housing directly in 90 front of the apex thereof is a socket member 28 having a concave pocket or recess 29 adapted to receive the rollers 21 when the tractor is backed for the purpose of backing a plow or other implement connected 95 with the hitching strap.

From the foregoing description, taken in connection with the drawing hereto annexed, the operation and advantages of this invention will be readily understood. It will be 100 seen that when the tractor begins to turn either to the right or to the left the housing of the hitching device will swing correspondingly until the rollers 21 will move over the track bars or flanges 20 in the direction 105 of one corner or the other according to the direction in which the turn is made, thereby shifting the point of draft in such a manner as to greatly facilitate turning. When the tractor and the implement drawn thereby 110

again straighten out, the initial or normal position of the rollers 21 will be automatically resumed. Should it be desired to back the implement drawn by the tractor, backward movement of the latter will place the rollers 21 in engagement with the pocket 29 of the socket member 28, and a straight push in a rearward direction will thus be exerted.

Having thus described the invention, what is claimed as new is:

1. In a device of the class described, a triangular housing comprising top and bottom plates having track flanges at the sides thereof, spacing blocks at the corners of said plates adjacent to the base, said blocks having rounded side walls producing pockets, a hitching strap having a portion extending within the housing between the track flanges, and track engaging rollers carried by said hitching strap.

2. In a device of the class described, a triangular housing comprising top and bottom plates having track flanges at the sides thereof, spacing blocks at the corners of said plates adjacent to the base, said blocks

having rounded side walls producing pockets, a hitching strap having a portion extending within the housing between the track flanges, and track engaging rollers carried by said hitching strap, said housing having a socket member located directly in front of the apex thereof, said apex extending in a rearward direction.

3. In a device of the class described, a housing of triangular form having track rails at the sides thereof, spacing members at the corners adjacent to the base of the housing, said spacing blocks having recesses formed therein, a hitching bar having lugs engaging said recesses, connecting bolts extending through the top and bottom plates of the housing, spacing blocks and the lugs, and hitching straps adjustably connected with the hitching bar, in combination with a hitching strap one end of which extends within the housing and is provided with track engaging rollers.

In testimony whereof I affix my signature.

WELFORD H. DIGGS.
